(57) **CLAIM**

The ornamental design for a combined portable chair and insulated container, as shown and described.

DESCRIPTION

FIG. 1 is a front view of the combined portable chair and insulated container showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top left side perspective view.

The broken lines in the figures show a cup holder, shoulder strap, and fabric design that form no part of the claimed design. The cross-hatching shading in the figures is fragmentarily shown for convenience of illustration, it being understood that the cross-hatching is uniformly continued over the surface on which it appears. The broken lines in the figures are for the purpose of illustrating portions of the combined portable chair and insulated container, which form no part of the claimed design.

1 Claim, 7 Drawing Sheets
